COMBINED RESUSCITATOR AND
INHALATOR

Clarence N. Erickson, Glendale, Calif.

Application March 15, 1935, Serial No. 11,301

12 Claims. (Cl. 128—29)

This invention relates to and has for a main object the provision of a combined resuscitator and inhalator arranged in a single compact unit and adapted for connection with a tank of oxygen and operative for use as a resuscitator for emergency treatment of persons who have been asphyxiated, drowned, suffocated or seriously shocked by electricity, or for use as an inhalator for supplying oxygen to the lungs in variable quantities depending upon requirements in different cases.

Reference is had to Letters Patent of the United States No. 1,893,670, granted to Monroe H. Goodner on January 10, 1933, for Resuscitators, 15 with respect to which the present invention embodies several distinct improvements, particularly in the provision of an inhalator in connection with the resuscitator, and otherwise as may appear hereinafter.

A further object is to provide an improved type of reducing valve between the oxygen tank and the resuscitator whereby the high pressure existing in the oxygen tank is reduced at the point of supply to a practicable minimum and which is 25 automatically operative and is yet capable of adjustment to meet varying requirements of use.

Another object is to provide an improved form of control means by means of which the instrument may be quickly adjusted as an inhalator or 30 as a resuscitator, and the inhalation and exhalation of a patient controlled accordingly.

This invention contemplates the provision, also, of improved means, including a sensitive and accurately operating diaphragm and a series of interconnected pistons operating in separate cylinders for so regulating and controlling the pressure and vacuum that the instrument is automatically adjustable to the varying lung capacity of different individuals.

40 Other objects will appear as the description of my apparatus progresses.

I have shown in the accompanying drawings a preferred form of apparatus embodying my invention, in which:

45 Fig. 1 is a sectional elevation of the apparatus, partly broken away, and disassociated from an oxygen tank, with the elements shown during a descending stroke of the pistons as in an inhalation cycle of operation;

50 Fig. 2 is a fragmentary sectional elevation of the same on line 2—2 of Fig. 1;

Fig. 3 is a sectional plan on line 3—3 of Fig. 1 showing a mask mounting and flexible connections between the apparatus and the mask;

Fig. 4 is a transverse section of the oxygen inlet, on line 4—4 of Fig. 1;

Fig. 5 is an elevation of the apparatus, partly in section in the plane of Fig. 1 and with the elements thereof positioned as during a descending 5 inhalation cycle of operation;

Fig. 6 is a sectional plan on line 6—6 of Fig. 1;

Figs. 7 and 8 are, respectively, sectional plans on lines 7—7 and 8—8 of Fig. 2;

Fig. 9 is a section of the control valve on line 10 9—9 of Fig. 2;

Fig. 10 is a section, in elevation, of the control valve, on line 10—10 of Fig. 2;

Fig. 11 is a fragmentary section, in elevation, of means for controlling the vacuum and oxygen 15 pressure in the cylinders, corresponding to but on a substantially enlarged scale with respect to the disclosure in Fig. 2;

Fig. 12 is a sectional elevation of the apparatus in the plane of Fig. 1 showing the elements positioned at the completion of an inhalation cycle 20 of operation;

Fig. 13 is a sectional elevation of a mask operatively connected with a suitable headpiece, in the plane of line 13—13 of Fig. 3, and arranged for 25 flexible connection with the main apparatus;

Fig. 14 is a perspective view of the apparatus arranged in a compact carrying case and operatively connected with a pair of oxygen tanks in 30 readiness for use.

In its simplest form the apparatus is arranged in a compact erect unit and includes an elongated vertical cylinder C having a detachable head H at its top which may be formed, as shown, of separable members 1, 2 and 3 suitably secured together in axial alignment and rigidly attached to the cylinder C, or to a top closure 4 fixed in the upper end of said cylinder, as shown in Fig. 1.

Cylinder C has a pair of telescoping cylinders 6 and 7 of different size longitudinally disposed 40 therein for slidably receiving pistons 9 and 10, respectively, together with a relatively larger piston 11 in the bottom of cylinder C. Cylinder 7 serves as a stem for piston 11 and is slidable through a partition 12 internally secured to cylinder C and packed around the cylinder 7, as by means of a gland 13, for preventing communication between the chamber 14 of cylinder C and chamber 15 of cylinder 6.

The upper end of cylinder 7 is fixed to and carries piston 9 while piston 10 is stationarily held on member 5 by means of a depending tube 16 and is positioned in chamber 17 of cylinder 7.

All of said pistons operate, as hereinafter explained in detail, for 55

regulating and effecting the inhalation and exhalation cycles of operation of the apparatus.

The application of vacuum to the chamber 14, is controlled by means of a sensitive diaphragm 5 D mounted in a chamber 18 formed within member 3 of head H and associated with a control valve V supported on said head. A reducing valve R is provided in head H within a chamber 19 for receiving a supply of oxygen from either 10 one of a pair of tanks T, T adapted to be held in a suitable carrying case 20 (see Fig. 14) and connected with chamber 19 through the reducing valve R in such a manner that the high pressure in said tanks will be reduced to a practical operating pressure for a resuscitating and inhalation apparatus.

To this end head H has a pair of oppositely extended arms 21, 21, each with a yoke 22 and a screw clamp 23 thereon by means of which the 20 necks of the tanks T are held on the arms in such a manner that oxygen from the tanks will flow through intake valves 24, 24 into a diametrical passage 25 formed in a portion 26 of the head and thence outwardly through a vertical passage 25 27 in a jet outlet 28. Reducing valve R is mounted on the bottom of head member 1 and includes a valve closure 29 which is urged upwardly into engagement with the end of jet 28 by means of springs 30 and is thus tensioned so 30 as to resist the discharge of oxygen from the jet into chamber 19, thereby limiting the pressure in said chamber to a predetermined extent.

Member 1 also supports a diaphragm 31 at its periphery and the central portion of the diaphragm is attached to a yoke 32 rigid with valve member 29. Head member 2 encloses a tensioning spring 33 which compresses between yoke 32 and a collar 34, and a manually adjustable screw 35 is adjustable on the hub of member 2 and 40 engages collar 34 for varying the pressure on valve member 29. Thus, the valve R will resist the high pressure of the oxygen in passage 25 and limit the volume and pressure supplied to the chamber 19, in accordance with the adjustment 45 of screw 35.

The oxygen from a tank T issues through jet 28 into chamber 19 and builds up a pressure against diaphragm 31, thereby compressing spring 33 which is under the control of screw 35. 50 The adjustment of said screw in opposite directions correspondingly varies the tension of spring 33 and the pressure against diaphragm 31. Springs 30 which bear upon the valve member 29 tend to close the valve seat of jet 28 and operate 55 against the tension of spring 33 so that when screw 35 is turned sufficiently in a given direction the tension of spring 33 is relieved. When screw 35 is turned to a maximum extent in an opposite direction the flow of oxygen is completely shut 60 off. Obviously, any desired intermediate pressure may be obtained by proper manipulation of screw 35.

The control valve V is interposed between the diaphragm chamber 18 and a mask M (Fig. 13) 65 and by means of flexible tube connections 36 and 37 the apparatus may be adapted and readily adjusted for operation as an inhalator or a resuscitator when the mask M is applied to the patient. Valve V is rotatably mounted on an extension 39 integral with head member 3, is tapered to fit a bore 40 and is operable by means of a handle 41 and has peripheral recesses 42 and 43 which terminate at the top and bottom of said valve and have their opposite extremities open at 70 diametrically opposite points on the periphery, as

shown in Fig. 2, for registration, respectively, with passages 44 and 45 in extension 39 with which the flexible tubes 36 and 37 communicate.

Tubes 36 and 37 connect at their other ends with passages 46 and 47 extended from the mask 5 mounting 38 and leading to chambers 48 and 49, respectively, in said mounting. Said chambers 48 and 49 have spring urged inhalation and exhalation valves 50 and 51 forming closures for ports 52 and 53, respectively, for regulating communication 10 between the chambers 48 and 49 and a common chamber 54 in the mask mounting 38 and thence with the interior of the mask M. Said valves are suitably caged and each has a spring 55 urging it into closed position. Auxiliary chambers 56 and 57 are also provided in member 38 15 above the chambers 48 and 49, respectively, chamber 56 having a spring urged safety valve 58 therein, and chamber 57 having a manually operable auxiliary exhalation valve therein, each of 20 the chambers 56 and 57 having one or more outlets 59 to the atmosphere. Mask M has an air cushioned rubber applicator M' adapted to fit over the face of a patient, as in other forms of apparatus for similar purposes. 25

It will be understood that it is the purpose of this invention to arrange the control means, including the diaphragm D and control valve V and associated mechanism, so that oxygen at a suitable pressure may be supplied to the lungs of a patient, regardless of his lung capacity, in regulated volume and in rhythmical impulses, and that the waste products of respiration may be exhaled by vacuum, both the pressure and vacuum being comprehensively controlled and 35 regulated to meet individual requirements. Therefore, chamber 18 in which the diaphragm D is located is always connected with a patient's lungs by means of a passage 60, valve V, tube 37, member 38 and mask M, and the pressure in 40 chamber 18 always corresponds to that in the lungs of a patient.

When the pressure in chamber 18 is raised above a predetermined point, diaphragm D is depressed, as shown in Fig. 1, and is held in a depressed position by means of a toggle device including a bifurcated lever 61 pivotally held at 62 and toggle arms 63 and 64 adapted to engage notches in a stud 65 at their inner ends. Said stud is fixed at its lower end to diaphragm D so 50 that the movement of the diaphragm will operate the toggles. Toggle 63 is coaxially held at 62 with lever 61 while toggle 64 is composed of a pair of slidably adjustable spring tensioned members pivotally held on lever 61 at 67. As shown 55 in Fig. 1 and elsewhere, the diaphragm D is clamped at its periphery to an internal portion of head H by suitable means.

Lever 61 supports at its free end a pair of valves 68 and 69 which, respectively, regulate the application of pressure to chamber 15 of cylinder 6 and the vacuum connection between chamber 14 of cylinder C and diaphragm 18. As shown in Fig. 11, valve 68 is composite and has an upper disc valve member 70 forming a closure for a 65 passage 71 in head member 5 and a lower conical valve member 72 forming a closure for a passage 73 in member 5. A stem 74 carries the valve members 70 and 72 at its lower end and is fixedly attached to lever 61 at its upper end and is 70 slidably at an intermediate point in a bore of member 5. Valve 68 is located in a chamber 75 which communicates by means of one or more passages 76 with a lower chamber 77 to which a tube 78 is connected and from which said tube 75

leads downwardly in cylinder C to and communicates with chamber 15 at a point 79.

Valve 69 is resiliently mounted on lever 61 above and for closing a vertical passage 80 in member 5 which communicates with chamber 14 of cylinder C by means of a tubular passage 81 leading to an inlet 82 in the bottom 83 of cylinder C.

For the purpose of description, pistons 9 and 11 will hereinafter be referred to as inspiratory and expiratory pistons, respectively, and their associated cylinders denominated accordingly, for the reason that the function of piston 9 is to raise piston 11 while the function of piston 11 is to create a vacuum in chamber 14 during an expiratory cycle. When the apparatus is used as a resuscitator and as an inhalator the gas is conveyed to and is discharged from the inspiratory cylinder 15 to the mask M.

Normally, pistons 9 and 11 do not move upwardly to the full limit of a stroke, piston 11 usually stopping short of an outlet 84 at the top of chamber 14 in cylinder C, but in the event of an overstroke of said pistons, means is provided on member 5 for elevating the diaphragm D slightly so as to initiate the upward movement thereof, as shown in Fig. 1. Said means includes a vertically slideable tube 85 having a flanged upper end 86 adapted to engage a pin 87 which is slideable in member 5 and adapted to engage the flanged bottom of stud 65 at the center of diaphragm D. Said diaphragm D is movable to a substantial extent in opposite directions to points beyond dead center positions of the toggles 63 and 64 and a trigger 88 is provided which is pivoted at 89 on member 5 and has a depending portion 90 seated in an aperture 91 in member 5 and engaged by a spring urged plunger 92 which tends to hold the trigger 40 resiliently in engagement with the diaphragm D, thereby limiting the downward movement of the diaphragm to a predetermined extent, so that when vacuum is created in chamber 14 the diaphragm may be readily elevated from the depressed position shown in Fig. 1. The tension of the plunger is regulated by means of a screw 93 between which and plunger 92 a spring 93' is compressed.

Tube 85 has a resiliently yieldable tongue 94 cut from or attached to the wall thereof and adapted to engage a peripheral hump 95 on stem 16 of piston 10, for locking the tube in its lowered position shown in Fig. 1, or in an elevated position as shown in Fig. 5, when the flange 86 of said tube is engaged by a plate 97 on piston 9. Tube 85 is restored to normally lowered position by means of the engagement of plate 97 with a flange 98 on the bottom of the tube. Tube 85 thus serves to hold diaphragm D upwardly until piston 11 reaches the bottom of chamber 14.

The function of piston 11 is to create a vacuum in chamber 14 for rendering the apparatus useful as a resuscitator when the mask M is applied to a lifeless patient. Piston 9 is operative in chamber 15 for the purpose of operating piston 11 when pressure is applied thereto, and piston 10 operates to preserve a constant pressure in chamber 17 which tends to restore piston 11 to normally depressed position in chamber 14, in the same manner as a spring would function when interposed between pistons 10 and 11.

The control mechanism is arranged to perform a dual function, namely, the regulation and control of the flow of oxygen from a tank T to the lungs of a patient and the outflow of the

products of respiration therefrom during a resuscitation operation, and the control of the flow of oxygen to a patient during an inhalation operation. A breathing bag 99 is detachably held on a nipple 100 of valve housing 39 and is in communication with a chamber 101 which has an air inlet 102 controlled by a valve 103, as shown in Fig. 2. In an inhalation operation the oxygen is directed to the bag 99 and then from the bag to the lungs of a patient, and the inflow and outflow of the oxygen causes the bag to contract and expand and thus provide means for visibly indicating the operation and the effect of the operation.

In cases where an excess of oxygen is required for a patient the valve 103 will remain closed but when breathing is induced to a point approaching normality the effort of the patient will induce a flow of air from the atmosphere through inlet 102 and valve 103.

Referring to Fig. 2, it will be observed that valve V has a peripheral recess 104 of arcuate form and of such extent that when the valve is properly positioned said recess will afford communication between gas passage 71 and a vertical passage 105 in the valve housing, whereby the gas is conducted from passage 71 through valve V to chamber 101 and thence to the breathing bag 99. Gas is exhausted from bag 99 through chamber 101, valve recess 42 and tube 36 to the mask mounting 38, as hereinbefore explained.

Valve V has an upper chamber 106 within the hub of handle 41 which is open to the atmosphere at a plurality of points, as by means of orifices 107, 107, etc. and the valve recess 43 is in constant communication with chamber 106 so that the products of respiration may be exhausted to the atmosphere through tube 37 leading from the mask M, passage 43 and chamber 106 during an inhalation operation, provided the auxiliary exhalation valve 58 on the mask is closed; otherwise when said valve 58 is open exhalation will be direct through chamber 57.

When the apparatus is used as an inhalator or as a resuscitator, gas is supplied to chamber 17 of piston stem 7 constantly for applying pressure to piston 11, thereby tending to depress said piston in its cylinder C. Accordingly, gas is fed through a vertical passage 108 which is open to the supply chamber 19 in head H at its upper end and is connected at its lower end with a passage 109 in tube 16 by means of a horizontal passage 110.

Obviously, as piston 11 is raised in its cylinder the air in that portion of cylinder C above said piston is expelled through the vent 84, and simultaneously air is expelled from the upper portion of chamber 15 through one or more vents 111 in cylinder 6 into chamber 112 of cylinder C from which the air is vented to the atmosphere through one or more vents 113. It will be understood that the chamber 114 below diaphragm D is vented to cylinder 6 by orifice 91, so that said diaphragm is free to raise when vacuum is applied thereto from chamber 14.

The operation of the apparatus, first as a resuscitator and then as an inhalator, is as follows:

When used as a resuscitator the pistons reciprocate vertically in their respective cylinders and serve to absorb the energy of the expanding oxygen from the reducing valve and for converting such energy into useful work in the form of a vacuum which removes the used gas from the lungs of a patient. As a resuscitator, it will be understood that it is necessary to create artificial

respiration by expanding and contracting the lungs of a patient rhythmically and regularly for alternately supplying oxygen to and for exhausting the products of respiration from the lungs 5 until natural respiration is gradually induced. As an inhalator, the apparatus is adapted to supply oxygen in sufficient volume to the lungs of a living patient who has been subjected to partial asphyxiation, shock or otherwise and the 10 apparatus merely assists the patient in performing the respiratory functions. The term inhalator herein used is a coined word employed to qualify the apparatus in respect to its functioning to supply oxygen to a patient as though said patient 15 had actually inhaled such oxygen.

When used as a resuscitator, oxygen from tank T will flow from chamber 19, through passages 108 and 110 into passage 109 of tube 16 and thence to chamber 17 of cylinder 7, thereby creating 20 pressure against piston 11 which tends to hold said piston at the bottom of its stroke in cylinder C, and simultaneously oxygen will flow from passage 108 into and from passage 110 into passage 73 and thence by valve 72 into chamber 15 25 and outwardly therefrom through passages 76 through chamber 77 into tube 78, and thence through inlet 79 to chamber 15 of cylinder 6. Thus, oxygen under pressure is applied to the 30 lower side of piston 9 in cylinder 6 for raising said piston and piston 11 to which it is connected. The area of piston 9 is substantially greater than the area of piston 11 exposed to the pressure of the oxygen; hence the pistons 9 and 11 will be simultaneously raised in their cylinders against the 35 downward pressure applied to piston 11 in chamber 17.

As pistons 9 and 11 are gradually raised, the air from their cylinders is expelled to the atmosphere, as hereinbefore described, and suction is 40 created in chamber 14 of cylinder C which is communicated to diaphragm chamber 18 by means of tube 81, thereby raising the diaphragm D and closing valves 69 and 70, while valve 12 is opened.

45 The upward movement of piston 9 is normally to a point short of actual engagement by flange 86 of tube 94 with plate 97 of piston 9, and in the event said piston is moved beyond its normal limit the engagement of piston 9 with flange 86 50 will operate safety pin 87 and effect an upward thrust of diaphragm D if in the meantime the vacuum in chamber 18 is not sufficient to accomplish the operation of the diaphragm. The extent to which the pistons 9 and 11 move upwardly corresponds to the capacity of the lungs 55 of a patient.

As hereinafter described, the extent of vacuum in chamber 18 is determined by the character 60 of the connection between the mask M and the patient. If said connection is loose the vacuum in chamber 18 will be insufficient to operate the diaphragm, hence upon an overstroke of the pistons 9 and 11 the safety pin 87 will insure the 65 operation of the diaphragm to the position shown in Fig. 5. As pistons 9 and 11 ascend in their cylinders a vacuum is applied to the lungs of a patient from chamber 14 by means of tube 81, chamber 18, passage 60, tube 37, valve 51 and mask M (see Fig. 3); thus the air and products of 70 respiration are exhausted from the lungs of a patient.

Under all conditions the pistons 9 and 11 will proceed to their extreme bottom positions, upon the completion of an exhalation cycle of operation and during such movement of the pistons a

leather valve 115 will expand and open as soon as peripheral orifices 116 in cylinder 7 reach a position below piston 10, as shown in Fig. 12, whereupon oxygen will be admitted into chamber 15 through said orifices, and thence to the patient 5 through tube 78, chamber 77, passages 76, chamber 15, by valve 70 which has been opened in the meantime due to return of the diaphragm to lowered position as shown in Fig. 5, through passage 71, thence through a vertical recess 117 (see Fig. 10 10 to and through valve passage 44, tube 36, inlet valve 50 of the mask mounting and mask M to the patient.

The admission of oxygen to the lungs of the patient will continue until sufficient pressure has 15 been built up in chamber 18 above diaphragm D to again reverse the diaphragm and valves 70 and 72. The alternate inhalation and exhalation cycles of operation will continue as long as the valve is adjusted as described and the mask 20 is applied to the patient. During the downward stroke of the pistons 9 and 11 the waste products of respiration under piston 11 in chamber 14 are forced by a yieldable cup leather valve 118 on piston 11 into the upper portion of chamber 14 25 from which it is discharged to the atmosphere through vent 84.

Preferably, the controlling mechanism is adjusted at the factory so that inhalation ceases 30 when a pressure of four ounces above atmosphere is attained and exhalation ceases when a pressure or vacuum of three ounces below atmosphere is attained, thereby insuring against injury to the lungs, distress or discomfort of a patient.

When the apparatus is used as an inhalator, 35 valve V is adjusted so that horizontal recess 104 will afford communication between passages 71 and 105 and the upper extremities of valve passages 42 and 43 will register, respectively, with tubes 36 and 37, for communication with mask 40 inlet and outlet valves 50 and 51, respectively. As an inhalator, the pistons 9 and 11 remain at the bottoms of their strokes, as shown in Fig. 12, and the orifices 116 in cylinder 7 are disposed 45 below the piston 10. Thus pressure of oxygen from chamber 17 will open leather valve 115 so that oxygen will flow into and from chamber 15 through tube 78, chamber 77, passages 76, chamber 75 by the open valve 70 to passage 71 and thence to valve recess 104 and passage 105 into 50 chamber 101, thence to and from the breathing bag 99 to and from valve passage 42 to the patient as described. The patient will exhale through the mask M and valve 51 through chamber 57 of the mask mounting to the atmosphere. If the 55 amount of oxygen supplied to a patient is less than that required, air from the atmosphere will be automatically supplied through auxiliary inhalation valve 103. Valve 58 which is arranged adjacent to the mask exhalation valve 51 is provided for the purpose of reducing the back pressure on the lungs of a patient when the machine is being used as an inhalator, and is manually adjustable in its seat. Obviously, when said valve is opened to a maximum extent, only atmospheric 60 pressure will have to be overcome in an exhalation operation.

What I claim is:

1. An apparatus of the character described comprising: an inspiratory cylinder and expiratory cylinder, pistons in said cylinders connected for simultaneous operation, a mask connected with said cylinders, means for constantly supplying a gas under pressure for application to said expiratory piston whereby said pistons are urged 70 75

to depressed positions in their cylinders, and manually operable means for regulating the supply of gas under pressure to said inspiratory cylinder and to said mask, including permanent connections between said cylinders and said mask, and valve means operable whereby the apparatus may be selectively used as a resuscitator while said pistons operate to provide artificial inspiration and expiration, respectively, and as an inhalator while said pistons are stationary for supplying gas to a living patient.

2. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a spring urged trigger disposed to resiliently limit the movement of the diaphragm, and a control valve connected with said inspiratory and expiratory cylinders and with said mask whereby on the opposite strokes of said pistons gas may be supplied to and exhausted from the lungs of a patient through said mask, in a resuscitating operation.

3. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, and means controlled by said diaphragm for directing the flow of gas to said pistons whereby the pistons may operate successively in opposite directions.

4. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, and means operative when said inspira-

tory piston is in a depressed position and said control valve is operated in a given direction whereby said pistons will remain stationary and gas will flow from said inspiratory cylinder to said mask in an inhalation operation.

5. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, connections between said expiratory cylinder and said vacuum chamber for creating vacuum in said chamber on the upstroke of said expiratory piston, and means operable by said inspiratory piston as the same is moved beyond a normal extent on its upward stroke, for actuating said diaphragm so as to reverse the mechanism to effect an ensuing inhalation cycle, in the event of a loose connection between said mask and a patient.

6. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, and an expandible and contractible breathing bag connected with said control valve for receiving and discharging the gas delivered to a patient and for indicating the respiration of the patient.

7. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient

- patient through said mask, in a resuscitating operation, an expansible and contractible breathing bag connected with said control valve for receiving and discharging the gas delivered to a patient and for indicating the respiration of the patient, said control valve having a valve associated therewith for admitting air from the atmosphere to the gas discharged from said bag when the gas supply exceeds a necessary volume.
10. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a spring urged trigger resiliently resisting movement of the diaphragm, a control valve connected with said inspiratory and expiratory cylinders and with said mask whereby on the opposite strokes of said pistons gas may be supplied to and exhausted from the lungs of a patient through said mask, in a resuscitating operation, said mask having inhalation and exhalation valves for regulating the supply of gas to and the discharge of the products of respiration from a patient.
9. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, said mask having inhalation and exhalation valves for regulating the supply of gas to and the discharge of the products of respiration from a patient, and an auxiliary safety valve associated with said mask for relieving the gas pressure delivered to the mask when a predetermined pressure is attained in the gas supply line to the mask.
10. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supply-

ing gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, said mask having inhalation and exhalation valves for regulating the supply of gas to and the discharge of the products of respiration from a patient, and an auxiliary valve associated with the exhalation valve of said mask and manually adjustable for relieving the back pressure on the lungs of a patient during an exhalation cycle of operation.

11. An apparatus of the character described comprising: a head provided with pressure and vacuum chambers closed against communication with each other, means for connecting said pressure chamber with a source of gas supply under high pressure, a reducing valve in said pressure chamber adjustable for limiting the pressure therein, a vacuum operated diaphragm in said vacuum chamber, an inspiratory cylinder, an expiratory cylinder, pistons in said cylinders connected for uniform operation, means for supplying gas from said pressure chamber to and for operating said pistons in opposite directions, a mask applicable to a patient, a control valve connected with said inspiratory and expiratory cylinders and with said mask whereby on the opposite strokes of said pistons gas may be supplied to and exhausted from the lungs of a patient through said mask, in a resuscitating operation, a stationary piston telescoping into said inspiratory piston and the connection between the inspiratory and expiratory pistons, a stem on said stationary piston having a passage connected with said pressure chamber for applying pressure to said expiratory piston, a member adjustable longitudinally on said stem and provided with detent means for holding it in raised and lowered positions, and means adapted to be engaged by said tubular member when the same is engaged and actuated by said inspiratory piston, for raising said diaphragm in the event of an overstroke of said inspiratory piston and occasioned by a loose connection between the mask and a patient.

12. A combined resuscitator and inhalator comprising pressure and vacuum chambers, means for connecting said pressure chamber with a source of gas supply under pressure, a pressure controlling valve in said pressure chamber adjustable for varying the pressure therein, a diaphragm in said vacuum chamber, an inspiratory cylinder and expiratory cylinder, pistons in said cylinders, means for supplying gas from said pressure chamber to and for operating said pistons in opposite directions, a mask applicable to the patient, a control valve connected with said cylinder and said mask whereby on opposite strokes of said pistons gas may be supplied to and exhausted from the lungs of a patient through said mask in a resuscitating operation, and means operative when said inspiratory piston is in one position and said control valve is manipulated in a given manner whereby said pistons will remain stationary and gas will flow from said inspiratory cylinder to said mask in an inhalation operation.

CLARENCE N. ERICKSON.
